UNITED STATES PATENT OFFICE.

JOEL T. HARDIN AND JAMES G. CLARK, OF FLINTVILLE, TENNESSEE.

WASHING-MACHINE.

1,199,270.

Specification of Letters Patent. Patented Sept. 26, 1916.

Application filed December 24, 1915. Serial No. 68,546.

To all whom it may concern:

Be it known that we, JOEL T. HARDIN and JAMES G. CLARK, citizen of the United States and subject of the King of England, respectively, residing at Flintville, in the county of Lincoln, State of Tennessee, have invented a new and useful Washing-Machine, of which the following is a specification.

10 The device forming the subject matter of this application is a washing machine and one object of the invention is to provide a main roller of novel form, the roller being of hollow construction, and being perforated, so that, as the roller exercises its function, the water may flow therethrough as the garments are operated upon.

Another object of the invention is to provide novel means whereby the main roller 20 is yieldably supported for rotation, and is made to coöperate with the auxiliary and supplemental rollers which are located below the main roller.

A further object of the invention is to 25 provide novel means for assembling the washing machine with a tub or like receptacle.

It is within the province of the disclosure to improve generally and to enhance 30 the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made 40 within the scope of what is claimed, without departing from the spirit of the invention.

In the accompanying drawing:—Figure 1 shows the invention in side elevation, parts 45 appearing in section, the structure being mounted upon a tub which appears in section; Fig. 2 is a bottom plan of the washing machine forming the subject matter of this application; Fig. 3 is a cross section taken 50 approximately on the line 3—3 of Fig. 1; Fig. 4 is a cross section taken approximately on the line 4—4 of Fig. 1.

In carrying out the present invention there is provided a base 1 carrying near its 55 ends, bolts 2 received in slots 3 formed in brackets 4 bearing against the lower face of

the base 1. The brackets 4 terminate at their ends in hooks 5 adapted to engage the upper edge of a tub 6. Wing screws 7 are threaded into the extremities of the hooks 5 and co-act with the tub 6 to hold the base 1 thereon. Wing nuts 8 are threaded onto the lower ends of the bolts 2 and serve to bind the inner ends of the brackets 4 against the lower face of the base 1.

From the foregoing it will be obvious that the brackets 4 may be adjusted longitudinally of the base, whereby the washing machine herein disclosed may be adapted for 65 tubs of different diameters.

Attached to and rising from the base 1 adjacent its ends are standards or end plates 9. Extended through the end plates 9 are securing elements 10 which may be bolts or rivets, these members serving to prevent the end plates 9 from splitting or warping, when the end plates are made of wood. In the upper ends of the plates 9, slots 11 are formed, a main shaft 12 being 80 detachably journaled in the slots 11. The main shaft 12 is provided with a crank 30 or other suitable means whereby a rotation may be imparted to the shaft. The ends of the main shaft 12 protrude beyond the standards 9 and are engaged by hooks 14 85 assembled with the upper ends of retractile springs 15, the lower ends of which terminate in eyes 16 passing downwardly into openings 17 formed in the base 1 near to the ends thereof. Securing elements 18, 90 which may be bolts or rivets, pass through the base 1 near to its ends and cross the openings 17, the securing elements 18 passing through the eyes 16 which are located at the lower ends of the springs 15. The 95 securing elements 18 therefor exercise two functions, since they constitute at once a means for retaining the springs 15 and for preventing a warping or splitting of the base 1, when the same is made of wood.

Supported on the main shaft 12 and located between the standards 9 is a main roller 19, ordinarily but not necessarily fashioned from wood, the exterior surface of the main roller 19 being provided with corrugations 20 disposed in a long, gradual spiral about the roller. The main roller 19 is hollow and embodies an internal chamber 21. In the wall of the main roller 19 between the corrugations 20 are formed perforations 22 which communicate with the chamber 21. The chamber 21 is enlarged at 100 105 110

the ends of the main roller 19, as shown at 23, thereby forming shoulders 24 against which abut end plates 25, having openings 26 communicating with the chamber 21, the end plates 25 being held in place by means of screws 27 or the like. The end plates are equipped with hubs 28 and it is in these hubs 28 that the main shaft 12 is immediately received, the hubs carrying set screws 29 engaging the main shaft 12, to the end that the main shaft and the main roller 19 may be connected for simultaneous rotation through the medium of the crank 30 or its equivalent.

15 Disposed below the main roller 19 are auxiliary rollers 31, provided at their ends with shafts 32 journaled in the standards 9. The auxiliary rollers 31 lie between supplemental rollers 33 provided with shafts 34 20 journaled in the end standards 9. The supplemental rollers 33 are somewhat larger in diameter than the auxiliary rollers 31.

In practical operation, the brackets 4 are slid endwise for adjustment, and are held 25 in adjusted positions by the wing nuts 8, so that the hooks 5 will coöperate with the upper edge of the tub 6, the screws being tightened up to hold the machine on the tub. The roller 19 is rotated through the 30 medium of the main shaft 12 and the crank 30, the shaft 12 rotating in the slots 11 of the standards 9. The main roller 19 is drawn downwardly by the action of the springs 15. The garments to be washed are 35 guided by the supplemental rollers 33 between the auxiliary rollers 31 and the main roller 19. The water carried by the garments is squeezed out and flows, along with

the dirt in the garments, through the perforations 22 in the main roller 19, into the 40 chamber 21, and out of the chamber through the holes 26 in the end plates 25. In this manner, a thorough washing of the garments is effected, with a minimum expenditure of effort.

45 For convenience in claiming the invention, the standards 9 and the base 1 may be described as a supporting structure.

Having thus described the invention, what is claimed is:—

50 A washing machine comprising a supporting structure; a roller journaled for rotation in the supporting structure; and opposed means wherewith the roller coacts; the roller being provided with external, 55 spirally disposed ribs defining grooves therebetween, and being hollow, there being perforations in the roller at the bases of the grooves, the perforations extending in lines which are disposed longitudinally of the 60 roller, and the perforations of each line being spaced apart, the perforations communicating with the interior of the roller; and end walls assembled with the roller, the end walls being provided with outlet perforations which are of greater diameter than the first specified perforations in the roller.

65 In testimony that we claim the foregoing as our own, we have hereto affixed our signatures in the presence of two witnesses.

JOEL T. HARDIN.
JAMES G. CLARK.
